STEEL CLIP FOR HOLDING COILED HAIR
Robert E. Davis, Sr., and Robert E. Davis, Jr., both
% Southland Sox Co., Fort Payne, Ala.
Filed Dec. 14, 1960, Ser. No. 75,341
1 Claim. (Cl. 132—41)

This invention relates to a tensioned spring steel clip for holding a coil of hair on a hollow cylinder during treatment of the coil of hair as in the curling thereof.

Many forms of so-called hair curlers have been proposed in the prior art, most of which are overly complex and impractical.

It is the primary object of the present invention to provide a tensioned spring steel clip universally applicable to the conventional form of hollow cylindrical member on which strands of human hair are coiled.

It is a more detailed object of the invention to provide a tensioned steel spring clip formed in a unitary structure and which requires the application of manual force to flex the clip in application to and removal from a hollow cylindrical member on which a strand of hair has been coiled.

Still more specifically it is a more detailed object of the invention to provide a tensioned spring steel clip including the thickened portion at one end formed into a hook, a flat bar, coextensive in length with the hollow cylinder to which the clip is to be applied with the free end of the bar, bent in the same direction as the hook, providing an angularly disposed extension so that the hook and angularly disposed extension embrace opposite ends of the hollow cylinder to which the clip is applied with the steel bar so tensioned that any one of a plurality of teeth carried thereby will be biased into locking with one end of the cylinder wall when the hook has been applied to the opposite end of the cylinder wall.

It is also an object of the invention to provide a tensioned spring steel clip for application to a hollow cylindrical member on which a strand of hair has been coiled which may be fabricated from spring steel as a unitary member which may be mass produced with each clip appropriately tensioned and tempered to insure long life and effective use.

Further and additional objects and advantages of the invention will become apparent as the description proceeds, which will be given in connection with the accompanying drawings wherein:

FIGURE 1 is a perspective view illustrating the spring steel clip of the invention applied to a conventional hollow cylindrical member.

FIGURE 2 is a side elevational view showing the cylindrical member in cross section with the steel spring clip in one position of adjustment thereof.

FIGURE 3 is a cross sectional view along the line 3—3 of FIGURE 2.

FIGURE 4 is a perspective view of the tensioned steel clip of the present invention in the form ready to be applied to a hollow cylindrical member carrying the coil of hair.

Referring to the drawings, the tensioned steel spring clip of the present invention is designated generally by the reference character A and the conventional type of cylindrical member is designated by the reference character B. The tensioned steel spring clip A is provided at its right hand end, as seen in FIGURES 1, 2 and 4, with a substantially thickened portion 10 which may be achieved in any desired manner such, for example, as by welding a short section of spring steel to the clip A at the hook end thereof. The thickened portion 10 is bent upon itself to provide the inwardly extending hook 11 adapted to be fitted over the end 12 of the wall 13 of the

2

hollow cylindrical member B. A flat bar 14, approximately coextensive in length with the cylinder B, has its flat face 15 positioned to engage a coil of hair on the cylindrical member B.

5 The flat bar 14 is provided with a right angle twist, as indicated at 16, so that beyond the right angle twist 16 the bar may be bent to provide the angular extension 17, having a toothed edge 18 provided with spaced teeth 19 facing the end 20 of the wall 13 of the hollow cylindrical member B. The angularly disposed extension 17 of the tensioned spring steel clip terminates in a projection 21 extending in the direction away from the end 20 of the hollow cylindrical member B, to which the spring steel clip A is adapted to be applied.

15 The spring steel clip A is adapted to be heat treated, tempered and tensioned so that the inner edge 18 of the angular extension 17 carrying the teeth 19 is at all times biased toward the hook 11. Conventional hollow cylindrical rollers, such as illustrated at B in the drawings, are 20 usually about 2 inches long and about $\frac{1}{8}$ of an inch in diameter. These dimensions may vary and likewise spring slips embodying the present invention may be supplied in varying lengths, each length being applied to hollow cylindrical members of corresponding dimension. The 25 length of the flat bar 14 determines the length of the hollow cylindrical member, such as B, to which the tensioned steel spring clip A of this invention may be applied.

In use a strand of hair is coiled upon a hollow cylindrical member such as B and then clamped on the cylindrical member by the tensioned steel spring clip A by merely applying the hook 11 to one end such as 12 of the hollow cylindrical member B and imposing a longitudinal manual pull through the medium of the projection 21 of the 30 angular extension 17 while pressing the flat face 15 of the bar 14 against the coil of hair until the desired degree of clamping pressure has been applied when the projection 21 is released and the selected tooth 19 is biased into locking engagement with the end such as 20 of the associated cylindrical member such as B. The clip cannot 35 be accidentally displaced since pressure imposed upon the flat bar 14 toward the cylindrical member B will only serve to lock the clip more tightly to the cylindrical member. A positive manual pull through the projection 21 40 on the angular extension 17 is required to effect the release of the teeth 19 from the end of the cylindrical member B.

It will be appreciated that the tensioned spring steel clips of the present invention can be mass produced, tempered and appropriately tensioned to provide long life. 45 The tensioned spring steel clip of the present invention is applicable to a variety of hollow cylindrical members and, of course, may be fabricated and supplied wholly independently of the hollow cylindrical member.

50 From the foregoing it will be apparent that we have provided a highly effective economically producible tensioned steel spring clip for clamping a coil of hair on a cylindrical member.

55 What we claim is:

60 A tensioned steel clip for holding a coil of hair on a hollow cylinder during treatment of said coil, said clip including a flat thickened portion at one end bent upon itself to form a hook to embrace the wall of the hollow cylinder at one end thereof and a flat bar, integral with 65 said hook, coextensive in length with the hollow cylinder to which the clip is to be applied, the free end of said flat bar being twisted at substantially a right angle and bent downwardly at substantially a right angle providing an angularly disposed extension adapted to embrace the opposite end of the hollow cylinder, said extension having in the edge thereof facing the cylinder a plurality of spaced teeth for selective engagement with the wall of the 70

hollow cylinder, said flat bar being so tensioned and twisted that any pressure exerted thereon to bias said flat bar toward the hollow cylinder will pivot said extension in a direction to bring any selected tooth into firmer locking engagement with the cylinder wall and means projecting from said angular extension for applying manual force to flex said bar to effect engagement and disengagement of any of said teeth with the wall of the cylinder.
